United States Patent Office

Des. 197,360
Patented Jan. 14, 1964

197,360

TAMPING MACHINE

Franklin M. Frohnauer, Jr., Columbus, Ohio, assignor to
Dyna-Quip, Inc., Columbus, Ohio, a corporation of
Ohio

Filed Jan. 22, 1962, Ser. No. 68,493

Term of patent 14 years

(Cl. D60—1)

FIG. 1

Des. 197,360

PAGE 2

FIG. 3

FIG. 4

FIG. 1 is a front elevational view of a tamping machine embodying my new design;

FIG. 2 is a side elevational view from the right thereof;

FIG. 3 is a side elevational view from the left thereof; and

FIG. 4 is a rear elevational view thereof.

The dominant features of my design reside in the portions shown in full lines.

I claim:

The ornamental design for a tamping machine, as shown and described.
